CLAIM

The ornamental design for a dancing cactus plush toy, as shown and described.

DESCRIPTION

FIG. 1 is a front elevational view of a dancing cactus plush toy showing my new design;

FIG. 2 is a rear elevational view thereof; and,

FIG. 3 is a left elevational view thereof;

FIG. 4 is a right side view thereof;

FIG. 5 is a top side view thereof;

FIG. 6 is a bottom plan view thereof;

FIG. 7 is a perspective view of a dancing cactus plush toy showing my new design; and,

FIG. 8 is another perspective view thereof.

The broken lines in the figures are for the purposes of illustrating portions of the dancing cactus plush toy, which form no part of the claimed design.
